C. F. KLINE

DOOR FASTENER

Filed Feb. 9, 1925

Inventor

Clarence F. Kline

By T. E. Shannon

Attorney

UNITED STATES PATENT OFFICE.

CLARENCE F. KLINE, OF AKRON, OHIO.

DOOR FASTENER.

Application filed February 9, 1925. Serial No. 7,770.

This invention relates to new and useful improvements in door fasteners. While adapted for use on doors of various kinds, the invention is particularly adapted to be used on the doors of automobiles and other vehicles.

Objects of the invention are to provide a door catch of simple, durable construction, which is composed of few parts and which may be provided at a low cost and which may be conveniently operated and will be very efficient in use.

A further object is to provide a door catch having a bolt and to provide new and improved mounting means therefor whereby the same will be held in proper alignment and to provide new and improved means for regulating the length of the bolt whereby it may be adjusted to sockets of different depths and may be adjusted to compensate for wear.

A further object is to provide a door catch having two bolts and to provide new and improved means whereby the same may be operated by a handle on either side of the door and to thereby provide a catch which will be very efficient in holding a door in alignment with the door jamb.

The above objects are accomplished and additional ends are attained by the novel construction, combination and arrangement of parts hereinafter described and illustrated in the accompanying drawing, wherein I have shown a preferred form of the invention, it being understood that the invention is capable of various adaptations and that changes and modifications may be made or substitutions resorted to which come within the scope of the claims hereunto appended.

In the drawings forming a part of this specification similar characters of reference are used to designate like parts as the same may appear in any of the several views and in which:

Figure 1 is a side elevational view of a door catch constructed in accordance with this invention, the same being shown with the lid of the catch casing removed and having the upper portion of the lock shown in central vertical section.

Figure 2 is a front elevational view of

same somewhat reduced in size and showing the operating handles attached thereto.

Figure 3 is a plan view of one of the parts shown in carrying out the invention.

Figure 4 is a perspective view showing the catch plate employed in carrying out the invention.

Proceeding now to a detailed description of the invention with reference to the particular adaptation shown in the drawings, the numeral 5 is used generally to denote the catch casing. The casing is preferably rectangular in form and is provided with a forward wall 5^a, a rear wall 5^b, a bottom wall 5^c and a top wall 5^d. The forward wall is provided with two spaced parallel bores 6 and 7. The walls of the plate 5^a are thickened adjacent each of the bores 6 and 7 to provide the inwardly projecting portions 8. The rear wall 5^b is provided with a bore 9 which is preferably of the same size as the bore 6 and is formed in said rear wall in axial alignment therewith. The rear wall is likewise provided with a similar bore which is formed therein in axial alignment with the bores 7. The numeral 10 denotes a cylindrical bolt which is mounted in the bore 6 and the numeral 11 denotes a like bolt which is mounted in the bore 7. Both the bolts 6 and 7 are reduced in diameter at the rear end thereof to provide a reduced portion 12. The reduced portion 12 is cylindrical in form and is exteriorly threaded with the screw threads 13.

The numeral 14 denotes an interiorly threaded cylindrical cap which is operatively positioned on the reduced portion 12 of each of the bolts 6 and 7. The cap 14 is cylindrical in form and is preferably of the same diameter as the bolts 10 and 11. Each cap 14 is provided at the rear end thereof with the outwardly projecting circumferentially extending flange 15. The flange 15 is preferably polygonal or is otherwise formed to provide means whereby the same may be engaged by wrench or other instrument for operating it on the reduced portion 12. The cap 14 is provided in the rear wall thereof with a bore 16 in which is mounted the screw 17 and each of the bolts 10 and 11 are provided with a longitudinally directed threaded bore 18 which

projects therein from the rear end thereof with the screw 17 being entered in said bore to lock each cap 14 on one of the bolts 10 and 11.

5 The numeral 19 denotes a connecting member which is provided adjacent the upper end thereof with the bore 20 and is likewise provided adjacent the lower end thereof with the bore 21. The bores 20 and 21 are parallel and are adapted to receive the bolts 10 and 11, the bolt 10 being mounted in the bore 20 and the bolt 11 mounted in the bore 21. The member 19 is thickened adjacent each end thereof to provide the rearwardly projecting portions 22 and 23. The portions 22 and 23 form a relatively wide bearing surface for the bolts 10 and 11 whereby the said member will be held at a right angle with each of the said bolts. The member 19 is suitably secured to each bolt 10 and 11, preferably by means of a pin 24 which is entered in a suitable bore extending through the member 19 and through said bolts.

10 The numeral 25 denotes lugs which project inwardly from the rear wall 5^b to provide a seat for a coil spring 26. One of the coil springs 26 is mounted on each bolt 10 and 11 and is arranged to be compressed between the rear wall 5^b and the member 19. The thickened portions 22 and 23 are each provided in the rear face thereof with an annular groove 27 which forms a seat for the forward end of the spring 26. The numeral 28 denotes a member which is rotatably mounted 15 in said casing so as to turn on an axis extending at a right angle to the axis of the bolts 10 and 11. The member 28 is provided with a lug 29 which is arranged to engage the member 19 whereby a rotary movement 20 of the member 28 will move the member 19 rearwardly in said casing and will cause the bolts 10 and 11 to be moved inwardly in the bores 6 and 7.

15 The member 28 is preferably provided with the squared opening 30 in which is mounted a square shaft 31, each end of the shaft being provided with a suitable handle 32 whereby the member 28 may be rotated and the bolts 10 and 11 operated as above 20 described. Each of the bolts 10 and 11 terminate at the forward end thereof in a spherical surface.

25 The numeral 33 denotes a catch plate which is provided with suitable sockets 34 and 35 for the reception of said bolts. The plate 33 is provided on the inner face thereof with inwardly projecting bosses 38 which are positioned thereon in axial alinement with the sockets 34 and 35, thus forming a 30 wall for said sockets. The inner wall of each socket 34 and 35 is shaped to conform to the spherical end of the bolts 10 and 11. The catch plate is provided at one edge thereof with outwardly projecting strike portions 36 and 37 which are turned to provide an in-

clined or curved surface adapted to engage the spherical surfaces of the bolts 10 and 11 and force the same inwardly in the bores 6 and 7 when the door is swung to a closed position.

70 It will be noted that the bolts 10 and 11 are held in an axial position by the relatively wide bearing members of the inwardly projecting portions 8 and the bores in the rear wall also form a bearing surface for the cap 75 members 9 whereby the said bolts are positively held in their proper position. The catch is preferably designed with the bolts 10 and 11 equally spaced from the center of the casing, and equally spaced from each edge 80 of the casing whereby the same may be inverted and the catch used for doors swinging in either direction without changing any of the parts within the casing.

85 Having thus illustrated my invention and described the same in detail, what I claim as new and desire to secure by Letters Patent is:—

1. In a door catch, a casing, a pair of spaced parallel bores in the forward wall 90 thereof, bolts slidably mounted in each of said bores, a member rigidly attached to each of said bolts and extending therebetween, bores in the rear wall of said casing, said bores being in axial alinement with the first 95 named bores, a cap threaded on the rear end of each of said bolts, each of said caps being mounted in one of the last named bores, a flange on each of said caps said flanges adapted to engage the rear wall of said casing to limit the forward movement of said bolts.

100 2. In a door catch, a casing, a pair of spaced parallel bores in the forward wall thereof, bolts slidably mounted in each of 105 said bores, a member rigidly attached to each of said bolts and extending therebetween, bores in the rear wall of said casing, said bores being in axial alinement with the first 110 named bores, a flanged cap threaded on the rear end of each of said bolts, each of said caps being mounted in one of the last named bores with said flange engaging the rear wall 115 of said casing, a member mounted in said casing at a point between said bolts for rotary movement on an axis extending at a right angle to said bolts, a cam on said member said cam adapted to engage said connecting member to move said bolts rearwardly in said casing.

120 3. In a door catch, in combination a suitable casing, a pair of spaced parallel bores in the forward wall thereof, a cylindrical bolt mounted in each of said bores, each bolt terminating at the forward end thereof in a spherical surface, a pair of like bores in the rear wall of said casing, said bores being formed in axial alinement with the first 125 named bores, each of said bolts being provided adjacent the rear end thereof with an 130

exteriorly threaded reduced portion, an interiorly threaded cylindrical cap mounted on each reduced portion, said cap provided with a flange adapted to engage the rear wall of said casing to limit the forward movement of each bolt and a strike plate having sockets conforming in shape to the outwardly pro-

jecting ends of said bolts whereby said caps may be operated to adjust said bolts in said sockets.

In testimony whereof I have hereunto set my hand.

CLARENCE F. KLINE.
